UNITED STATES PATENT OFFICE.

LEO H. JUNKER, OF PELHAM, NEW YORK.

INDIVIDUAL-PACKAGE DISPLAY CARD.

Application filed June 25, 1921. Serial No. 420,369.

To all whom it may concern:

Be it known that I, LEO H. JUNKER, a citizen of the United States, residing at Pelham, in the county of Westchester and State 5 of New York, have invented certain new and useful Improvements in Individual-Package Display Cards, of which the following is a specification.

This invention relates to advertising devices and more particularly to a self-supporting advertising display card adapted for use with and in displaying an individual package of goods, as a can of paint or varnish, a can or jar of food, etc., but the invention 15 may also be utilized in other ways.

The principal objects of my invention are to provide a simple, inexpensive display card that will animate and more effectively display merchandise such as a container of 20 paint, food, etc., as by producing the appearance of an open container, with the contents exposed, and a device dipping therein for manipulating the contents.

Generally speaking, my improved display 25 card comprises a base and a tongue projecting up therefrom, the base fitting the top of the container and being colored or otherwise printed to resemble the contents, and the tongue being either a decorated panel 30 carrying advertising or desirably cut to simulate an article, such as a paint brush, spoon or the like for manipulating the contents of the container.

The objects and novel features of the invention will be more clearly understood 35 from the following description taken with the accompanying drawing, in which—

Fig. 1 is a perspective view illustrating a paint can carrying a display card embodying my invention,

Fig. 2 is a plan view of the blank display card, and

Fig. 3 is a plan view of another blank display card embodying my invention.

The improved display device is desirably die cut from a single piece of sheet material such as paper, cardboard, sheet metal or the like, but may be made in other ways as by molding it of suitable material such as 45 papier mâché. Referring to Figs. 1 and 2 of the drawing, the display device comprises a base B and a tongue T cut from the same sheet and integrally united along a score line L where the blank is bent so that when 55 the card is ready for use the tongue extends upwardly at an oblique angle from the plane

of the base. The general outline of the major portion of the base conforms to the top of the individual container upon which the device is to be supported, and in the particular forms illustrated is circular.

In the flat blank the tongue T projects beyond the margin of the base B, and two substantially parallel cuts or slits R and S extend from the margin of the base inwardly to the dotted score line L. The joint line L extends substantially perpendicularly across the geometrical axis and through the geometrical center of the base but is within the margin of the base and in the particular form shown such joint is within the circle defined by the major portion of the base. Parts B' and B'' of the base extend rearwardly of the line L or joint of the base and the tongue and act as braces in the plane of the base to make the device more stable. As shown, the base is in effect a circular disk with the tongue secured thereto along one of its diameters. A recess E is left within the base between the braces B' and B'' but the upwardly projecting tongue will practically conceal it, especially when the card is viewed from in front.

The blanks may be printed or lithographed in the sheet and die cut or blanked out in the shape desired, the slits R and S and the dotted score line L being formed at the same time. The printing or lithographing and the shape of the blank may vary, the upper surface of the base being desirably 85 colored to resemble the goods in the container and the tongue being desirably shaped to resemble means for manipulating the contents of the container. As illustrated in Figs. 1 and 2, for example, the device is formed and colored to simulate a 90 brush dipping in an open can P of paint, the upper surface of the substantially circular base and a portion of the lower end of the tongue being printed in the color of the paint, the tongue also having the shape and color of a brush and its handle. In the particular arrangement shown, the base of the device seats in, and its edge frictionally engages, the wall of a well known type of de- 95 pressed frictional can cover C. However, the device is essentially a self-supported display card. It will be understood that the display device may also take other forms, as for example as a display card for a jar 100 or jam the base may have its upper surface printed and colored to correspond to the 110

jam and the tongue formed to resemble means, such as a spoon or a ladle dipping therein, for manipulating the jam. Furthermore, as shown in Fig. 3, the tongue 5 may simply be in the form of an upwardly extending panel T', the upper surface of the base being colored or printed to simulate the contents of the container and the front of the tongue carrying advertising, if desired, or itself colored to serve as a color panel.

While one form of my improved display device is shown and described in detail, it 15 will be understood that various changes may be made therein without departing from the invention or sacrificing any of its advantages.

I claim:

1. A display device comprising a base 20 adapted to be supported upon an individual package of goods and a tongue projecting upwardly from within the outline of the major portion of said base and simulating an article projecting from within said pack- 25 age.

2. A display device comprising a base and an upwardly projecting tongue connected thereto, such base having one or more portions in the plane thereof projecting rear- 30 wardly of the line of connection of said tongue and base and constituting brace means for said device.

3. A display device comprising a base adapted to be mounted upon a package of 35 goods, and a tongue projecting upwardly from said base and constructed to simulate means for manipulating the contents of such package.

4. A self-supporting display device 40 formed from a single piece of sheet material and comprising a base the major portion of which is substantially circular, and an upwardly projecting tongue integrally joined to said base along a line within the 45 circle defined by the major portion of said base.

5. A display device formed from a single

piece of sheet material and comprising a base adapted to be mounted upon and conforming to the top of a package of goods, 50 and a tongue projecting upwardly from said base and constructed to simulate means for manipulating the contents of said package.

6. A display device comprising a base adapted to be mounted upon a package of 55 goods, and a tongue projecting upwardly and rearwardly from said base and constructed to simulate means for manipulating the contents of said package, said device having bracing means arranged rearwardly 60 of said tongue.

7. A display device comprising a base constructed and arranged to fit in the depressed top of a can or the like, and a tongue projecting upwardly from said base and con- 65 structed and arranged to simulate means for manipulating the contents of such can.

8. A display device comprising a base constructed and arranged to frictionally fit in the depressed top of a can or the like and 70 having its upper surface arranged to simulate the contents of such can, and a tongue projecting upwardly from said base and constructed and arranged to simulate a brush dipping in the contents of said can. 75

9. A display device formed from a single piece of sheet material and comprising a base adapted to be mounted upon and conforming in general outline to that of the top of a package of goods such as a can, the 80 upper surface of said base having the appearance of the contents of said package, and a tongue projecting upwardly from said base and constructed and arranged to simulate means for manipulating the contents of 85 said package.

10. A display device comprising a base simulating a portion of a package of mer- 90 chandise, and a tongue projecting upwardly from said base and simulating an article extending into said merchandise.

In testimony whereof I affix my signature.

LEO H. JUNKER.
